(57) **CLAIM**

The ornamental design of a wall rack for holding plotter/blue print rolls, as shown and described.

DESCRIPTION

FIG. 1 is an isoplane view of the wall rack for holding plotter/blue print rolls.

FIG. 2 is a front view of the wall rack for holding plotter/blue print rolls.

FIG. 3 is a back view of the wall rack for holding plotter/blue print rolls.

FIG. 4 is a left side view of the wall rack for holding plotter/blue print rolls.

FIG. 5 is a right side view of the wall rack for holding plotter/blue print rolls.

FIG. 6 is a top view of the wall rack for holding plotter/blue print rolls. The bottom view is identical to the top view of the wall rack for holding plotter/blue print rolls.
